CLAIM

The ornamental design for a cordless iron, as shown and described.

DESCRIPTION

FIG. 1 is a view in perspective of a cordless iron.

FIG. 2 is a front plan view of the cordless iron of FIG. 1.

FIG. 3 is a rear plan view of the cordless iron of FIG. 1.

FIG. 4 is a top end view of the cordless iron of FIG. 1.

FIG. 5 is a side view of the cordless iron of FIG. 1.

FIG. 6 is a side view of the cordless iron of FIG. 1; and,

FIG. 7 is a bottom view of the cordless iron of FIG. 1, the broken lines shown are for illustrative purposes only and form no part of the claimed design.

Broken lines in the drawing form no part of the design to be patented.
